CLAIM

The ornamental design for a battery and charging dock assembly as shown and described.

DESCRIPTION

FIG. 1 is a perspective assembling view of a battery and charging dock assembly showing my new design;

FIG. 2 is a perspective exploded view thereof;

FIG. 3 is a perspective view of the battery, shown disassembled for ease of illustration;

FIG. 4 is a front view thereof;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a second perspective view thereof;

FIG. 11 is a perspective view of the charging dock, shown disassembled for ease of illustration;

FIG. 12 is a front view thereof;

FIG. 13 is a rear view thereof;

FIG. 14 is a left side view thereof;

FIG. 15 is a right side view thereof;

FIG. 16 is a top view thereof; and,

FIG. 17 is a bottom view thereof.

The broken lines shown in the figures are for the purpose of illustrating portions of the battery and charging dock assembly and form no part of the claimed design.
